UNITED STATES PATENT OFFICE.

BERGET HENRI BLOCKSOM, OF MICHIGAN CITY, INDIANA.

CARPET LINER.

Application filed March 2, 1923. Serial No. 622,274.

To all whom it may concern:

Be it known that I, BERGET HENRI BLOCKSOM, a citizen of the United States, residing at Michigan City, in the county of Laporte and State of Indiana, have invented a new and useful Improvement in Carpet Liners, of which the following is a specification.

My invention relates to an improved form 10 of liner or pad for use under carpets to cushion the same and for other uses in which it is desirable to employ a resilient pad. My invention consists essentially of a layer 15 of intertwined resilient fibers having preferably a considerable degree of elastic action such that the sheet of material tends to resume and maintain its original thickness after being compressed and I find for this purpose that a pad or layer of curled 20 animal hair serves admirably. I have found that the pad of resilient fibers is not substantial enough for all purposes, such as carpet liners, unless protected in some manner and my invention more specifically 25 consists in providing the layer of resilient material with a layer of backing material on one or both of its faces, said backing material being preferably fibrous and loosely woven and having its threads or fibers at 30 intervals extending through the sheet of resilient material, the loops of the threads or fibers extending through the resilient material tending to hold the backing layer or 35 layers and resilient material together, thus facilitating handling the liner or resilient pad and preventing undue disintegration 40 during shipment and use. In cases where both sides of the curled hair pad are protected with layers of fibrous material such 45 for example as burlap, the threads of the burlap are readily forced through the curled hair pad and also through the layer of burlap on the other side of the pad leaving projecting loops that have the effect of interlocking the body portion of the pad and the 50 protecting layers on its surfaces. It will be understood that the loops referred to may be forced through the pad from one or both of the protecting layers of burlap as desired.

My invention will best be understood by reference to the accompanying drawings showing a preferred embodiment thereof in which

Fig. 1 is a transverse sectional view

through a part of a pad having a protective layer on one of its surfaces,

Fig. 2 shows in a view similar to Fig. 1, a pad provided with a protective layer on both of its surfaces, and

Fig. 3 is a detail view of a form of needle 60 that may be employed to force the threads of the protective material through the pad.

Similar numerals refer to similar parts 65 throughout the several views.

As shown in Fig. 1, the sheet of resilient material, preferably curled animal hair, is indicated at 10 and on one of its surfaces a protective layer 11 is shown consisting preferably of coarse fabric, such as burlap. 70 At 11^a a loop of the thread or fabric of the layer of material 11 is indicated as having been forced through the sheet of material 10 by means of a needle 12, operated preferably by suitable machinery, not shown as it forms 75 no part of the present invention. A second loop 11^b is indicated after it has been similarly formed from the layer of material 11 and forced through the sheet of material 10. It will be understood that loops 11^b are 80 formed in the manner described over the entire surface of the sheet material 10, the spacing of the loops being such as to hold the sheet of material 10 and the protective 85 layer 11 securely together so that the sheet of material 10 is materially reinforced by the layer 11.

As shown in Fig. 2 the sheet of resilient material 10 is provided with a first protective layer, preferably of fabric such as burlap, as described in connection with Fig. 1 and also on its other surface with a second similar layer of protective material 13 and in this case the loops 11^b formed as described in connection with Fig. 1 extend 90 through the second protective layer 13 and similar loops 13^b, 13^b are shown as formed from the layer 13 and extending through the sheet of material 10 and also through the protective layer 11. This construction 95 has the advantages over that shown in Fig. 1, of protecting both sides of the resilient material 10 and furthermore the interlocking of the loops referred to is more positive than it is with the construction shown 100 in Fig. 1, for the reason that each loop extends through and interlocks with the fabric of the other protective layer of material. In this case as in the construction shown in Fig. 1 the loops may be given any 105 110

desired spacing over the entire surface of the pad so that the protective layers are held securely to the body portion of the pad as may be required for any particular purpose to which the pad is put. I find that resilient pads constructed as described are very effective for use as carpet liners, that is for laying on a floor under a carpet or rug since the resilient nature of the body portion of the pad gives an easy and pleasing effect when walking on the carpet, the material does not easily mat, but on the other hand tends to maintain its original shape and furthermore the protective layer or layers of material secured to the resilient material, protects the resilient material from disintegration which would otherwise quickly occur from repeatedly walking on the rug. It will further be observed that the resilient pads constructed as described are quite substantial in nature and may readily be made in any desired lengths and widths and may readily be formed in rolls for purposes of shipping, 25 without danger of damage to the pads.

As shown in Fig. 3 the needle 12 may be of any desired conformation as long as it is provided with a hook 12^a projecting from the body portion of the needle sufficiently to engage and carry with it one of the threads 11^a of the fabric used as a protective layer. The needle may be operated by any convenient means, whether manually or by suitable machinery and its operation in forming any one of the loops referred to is to engage a thread of the fabric of the protecting layer as the needle is being forced through the pad and carrying the thread through the opposite side of the pad, thus forming a loop of the kind referred to above, projecting from the surface of the pad opposite to that on which the protective layer from which the thread is drawn, is disposed. The loop is retained in the position indicated in the drawings upon withdrawal of the needle, by the engagement of the thread or fiber of the loop with the material of the sheet 10 and also where two protective layers of material are employed, by engagement with the threads or fibers of the layer of protective material on the side of the pad adjacent the loop. In this manner the loops are interlocked with the resilient material of the sheet 10 and also where two protective layers are employed, with the threads or fibers of the other protective layer.

In manufacturing resilient pads as above described, where the layer of resilient fiber is relatively thick, or the threads of the protective fabric are relatively non-yielding, the forming of the loops described from the threads of the protective fabric may break these threads or stretch these threads by displacing the fibers of the threads longitudi-

nally thereof relatively to each other, without however, detracting materially from the value of the finished pads, since the interlocking action of the loops is quite as effective for the purposes above described as though the threads remained unbroken or unstretched; in other cases, where the layers of resilient fiber are comparatively thin and where the protective fabric consists of loosely twisted threads as found in burlap, the loops may be formed as above described without breaking the threads and without materially changing their original form.

While I have shown my invention in the particular embodiment above described, it will be understood that I do not limit myself to this exact construction as I may employ equivalents known to the art at the time of the filing of this application without departing from the scope of the appended claims.

What I claim is:

1. In a pad of the kind described, the combination of a body portion comprising a sheet of fibrous resilient material, and a sheet of protective material on one of its surfaces comprising interwoven threads, said threads at intervals extending from said protective layer through the body portion of the pad and forming loops at the opposite surface of said pad.

2. In a pad of the class described, the combination of a body portion comprising a sheet of resilient fibrous material, and a protective layer of material on each surface of said body portion having threads extending at intervals through the said body portion and in the form of loops through the opposite layer of protective material.

3. In a pad of the class described, the combination of a body portion comprising a sheet of resilient fibrous material, and a protective layer of material on each surface of said body portion, one of said layers of protective material having threads extending at intervals through said body portion and forming loops extending through the other layer of protective material.

4. In a pad of the class described, the combination of a body portion comprising a sheet of curled animal hair, and a layer of protective material on one of its surfaces comprising coarsely woven fabric having its threads at desired intervals projecting through said body portion in the form of loops terminating adjacent the other surface of the pad.

5. In a pad of the class described, the combination of a body portion comprising a sheet of curled animal hair, and a protective layer on each surface of said body portion comprising coarsely woven fabric having its threads at desired intervals extending through said body portion in the form of

loops through the other layer of protective material.

6. In a pad of the class described, the combination of a body portion comprising a sheet of curled animal hair, and a protective layer on each surface of said body portion comprising coarsely woven fabric, the threads of the fabric of one of said protective layers being extended at intervals over

the surface of the pad through the body portion thereof and in the form of loops extending through the other layer of protecting material.

In witness whereof, I hereunto subscribe my name this 22nd day of February, A. D. 15

1923.

BERGET HENRI BLOCKSOM.
